UNITED STATES PATENT OFFICE.

BENJAMIN F. FLEGEL, OF RACINE, WISCONSIN.

CULINARY TIMING APPARATUS.

1,097,753.

Specification of Letters Patent. Patented May 26, 1914.

Application filed November 17, 1913. Serial No. 801,455.

To all whom it may concern:

Be it known that I, BENJAMIN F. FLEGEL, a citizen of the United States, and resident of Racine, in the county of Racine and State of Wisconsin, have invented certain new and useful Improvements in Culinary Timing Apparatus; and I do hereby declare that the following is a full, clear, and exact description thereof.

My invention consists in what is herein particularly set forth with reference to the accompanying drawings and pointed out in the claims of this specification; its object being to provide simple, economical and efficient culinary timing mechanism, especially designed for the use of restaurant cooks to indicate how long eggs in one or more lots are to be boiled and for automatic audible signaling when the completion of a predetermined variable interval of time for the boiling of each lot or order of the eggs occurs.

Figure 1 of the drawings represents a front elevation of my improved culinary timing mechanism; Fig. 2, a sectional view of the same indicated by line 2—2 in the next described illustration; Fig. 3, a similar view indicated by line 3—3 in Fig. 2; Fig. 4, a front elevation of a clock-hand of the mechanism in gripping slip-fit upon an arbor that is shown in cross-section; Fig. 5, a similar view of an electric-circuit contact-blade of said mechanism, and Fig. 6, a perspective view of a receptacle containing eggs and having a handle numbered to correspond with one of a series of hands of a clock constituting part of the aforesaid mechanism.

Referring by numerals to the drawings, 15 indicates a casing containing a preferably twin main-spring eight-day clock 16, an electric-bell 17 and a dry-battery 18; all in a single circuit that includes a series of posts 19, the wiring 20, 21 and 22 of the circuit being clearly shown in Fig. 2. The 20 minute-hand arbor 23 of the clock 16 extends forward of the center of a dial 24 on the front of the casing 15, the dial being shown as having each quarter thereof provided with a minute-scale numbering from 0 to 14 inclusive contra-clockwise of said dial. Pivoted at quarter-circle intervals of the dial adjacent to its center are radial pointers 25, one for each minute-scale of said dial, and in gripping slip-fit on the 25 arbor 23 are a series of indexed hands 26, said hands being held between washers 27

on said arbor through which a key 28 extends in front of the forward washer. As a matter of detail, the pivot of each of the pointers is a rivet extending at its rear end through a spring disk 25' against which it is upset and a suitable washer is arranged between each pointer and the dial. Owing to this construction and arrangement of parts the pointers are frictionally held in adjusted position. As another matter of detail each hand 26 is first centrally bored through the butt-end thereof to provide an arbor-engaging opening, after which it is longitudinally kerfed through the opening 70 and then compressed to reduce the original diameter of said opening, whereby provision is had for gripping slip-fit of the hand on its arbor against which it has side friction, it being understood that the several 75 hands pass continuously clockwise of the dial, except that any of said hands may be manually moved in the opposite direction to set it in register with an adjusted pointer, and being released by the operator, it again 80 moves clockwise of said dial. The posts 19 extend through the casing at quarter circle intervals in register with the zero marks of the minute-scales upon the dial 24, and sleeve-ends of electric contact-blades 29 are 85 engaged by said posts. Extending from the casing through the dial are stop-pins 30 against which to abut the contact blades in the path of said hands. As a matter of detail each post 19 is of reduced diameter for 90 a limited distance back of its outer end to provide an annular groove 19' with which to engage an offset portion of the sleeve-end of a contact-blade, said blade being kerfed through the sleeve thereof and that portion 95 31 of said sleeve forward of the kerf bent out of line with the remainder thereof. Forcing of the blade-sleeve onto a supporting pivot-post results in a spring of the offset portion of said sleeve into engagement with 100 the post-groove to secure the blade against accidental displacement.

Designed to accompany the timing and audible signal mechanism above specified are non-corrosive wire baskets similar to the one shown by Fig. 6, and the handle 32 of each basket is provided with a tag 33 indexed to correspond with a hand of said mechanism.

From the foregoing it will be understood 110 that each pointer 25 and hand 26 is pivotally adjustable, but the pointer remains

stationary in adjusted position while the hand is being driven clockwise of the adjacent dial. In practice a pointer and a hand having the same number as a basket 5 containing an order of eggs are set counter-clockwise to register with a degree of one of the minute-scales on the dial 24 that agrees with the number of minutes the eggs are to be boiled, said basket with its contacts being at the same time submerged in boiling 10 water and a contact-blade 29 swung into the clockwise path of said hand. At the instant the hand touches the blade, the electric-circuit is closed to cause ringing of the bell and thus signal completion of the pre-determined interval of time for the boiling 15 of the eggs, which interval is indicated in minutes by the previously adjusted pointer. In Fig. 1, the pointer adjacent to the hand 20 No. 1, is shown set at 4 in the left upper minute-scale of the dial and the hand No. 1, previously set in register with said pointer, is on its way to touch against the contact-blade 29 in its path, this juxtaposition of 25 hand and blade occurring four minutes after the eggs in the basket No. 1 have been put into boiling water. When the bell rings, the cook swings said contact-blade out of the path of the opposing clock-hand and at the 30 same time withdraws the eggs from the boiling water. If in the meantime another order of eggs is to be boiled for a predetermined interval of time within a fixed limit, another clock-hand having the number 35 of the basket for the new order of eggs is properly adjusted counter-clockwise with an adjacent pointer as above explained, and a contact-blade swung into the path of said hand at the time of putting said eggs into 40 boiling water. Likewise orders of eggs up to the capacity of the timing-mechanism may be in the process of boiling, and the completion of the interval of time for the boiling of any of said orders being signaled, 45 the cook has only to glance back of the minute-hand then in touch with a contact-blade to determine, by the adjacent pointer, the number of minutes the eggs of that order have boiled, which number of minutes is 50 called back with the serving of said eggs to the person taking said order.

The timing-mechanism herein shown and described is one of four order capacity, but it is obvious that its capacity may be indefinitely increased by a mere addition of 55 minute-scales on the dial, adjustable pointers, indexed minute-hands, pivotal contact-blades, and egg-baskets indexed to correspond with said minute-hands. It is also to be understood that the timing-mechanism 60 may be of less capacity than that herein shown.

I claim:

1. A culinary timing-mechanism comprising 65 a clock, an audible signal and an adjust-

able contact all in an electric-circuit; a dial having a minute-scale contra-clockwise thereof, a pivotally adjustable pointer for indicating a selected minute of the scale on the dial, and a hand in pivotally adjustable 70 automatic gripping engagement with the minute-hand arbor of the clock forward of said dial to be set in register with the adjusted pointer and thereafter have clockwise movement into touch with said contact set 75 in its path.

2. A culinary timing-mechanism comprising a clock, an audible signal and adjustable contacts all in an electric-circuit; a dial having a plurality of minute-scales contra-clockwise thereof, pivotally adjustable pointers for indicating selected minutes of the scales on the dial, and hands in pivotally adjustable automatic gripping engagement with the minute-hand arbor of the clock forward 80 of said dial for individual setting in register with an adjusted pointer and which thereafter has clockwise movement into touch with one of said contacts set in its path. 85

3. A culinary timing-mechanism comprising a casing provided with a front dial having contra-clockwise minute-scales at intervals thereof, a clock, an audible signal and battery within the casing; radial pointers 90 in pivotally adjustable connection with the dial for indicating selected minutes of said scales, contact-blades pivotally adjustable on posts of said casing wired in circuit with the clock, signal and battery; and hands in pivotally adjustable automatic gripping engagement with the minute-hand arbor of 95 said clock forward of said dial for individual setting in register with an adjusted pointer and which thereafter has clockwise 100 movement into touch with one of said contacts set in its path. 105

4. A culinary timing-mechanism comprising a casing provided with a front dial having contra-clockwise minute-scales at intervals thereof, a clock, an audible signal and battery within the casing; radial pointers 110 in pivotally adjustable connection with the dial for indicating selected minutes of said scales, contact-blades pivotally adjustable 115 on posts of said casing wired in circuit with the clock, signal and battery; a stop in the pivotal path of each blade, and hands in pivotally adjustable automatic gripping engagement with the minute-hand arbor of 120 said clock forward of said dial for individual setting in register with an adjusted pointer and which thereafter has clockwise movement into touch with one of said contacts set in its path. 125

5. A culinary timing mechanism comprising annularly grooved posts in an electric-circuit, and contact blades each of which is longitudinally kerfed through a sleeve-end thereof and has a portion of the sleeve offset 130

for engagement with the groove of one of said posts upon which the blades are pivotally adjustable to be in or out of the path of driven hands of said timing-mechanism
5 also in said electric-circuit.

In testimony that I claim the foregoing I have hereunto set my hand at Milwaukee

in the county of Milwaukee and State of Wisconsin in the presence of two witnesses.
